CLAIM

We claim the ornamental design for a portable grill, as shown and described.

DESCRIPTION

FIG. 1 is a perspective side view of the ornamental appearance of the portable grill;

FIG. 2 is a front view of the portable grill shown in FIG. 1; FIG. 3 is a side view of the portable grill shown in FIG. 1; and, FIG. 4 is a top view of the portable grill shown in FIG. 1.
